US00D732775S

(12) **United States Design Patent**
Chung et al.

(10) **Patent No.:** US D732,775 S
(45) **Date of Patent:** ** Jun. 23, 2015

(54) **MAIN BODY FOR CLOTHES MANAGEMENT APPARATUS**

(71) Applicant: **LG Electronics Inc.**, Seoul (KR)

(72) Inventors: **Wookjun Chung**, Seoul (KR);
Jaemyung Lim, Seoul (KR);
Byeongkook Kim, Seoul (KR); **Junghoi Choi**, Seoul (KR)

(73) Assignee: **LG Electronics Inc.**, Seoul (KR)

(**) Term: **14 Years**

(21) Appl. No.: **29/486,722**

(22) Filed: **Apr. 2, 2014**

(30) **Foreign Application Priority Data**

Jan. 10, 2014 (KR) 30-2014-0001615
(51) **LOC (10) Cl.** **15-05**
(52) **U.S. Cl.**

(57) **CLAIM**

The ornamental design for a main body for clothes management apparatus, as shown and described.

DESCRIPTION

FIG. 1 is a top-right perspective view of a main body for clothes management apparatus showing our new design; FIG. 2 is a front view thereof;

FIG. 3 is a bottom-right perspective view thereof; FIG. 4 is a top-left perspective view thereof;

FIG. 5 is a bottom-left perspective view thereof; and, FIG. 6 is a top right perspective view showing the design in use.

The broken lines are for illustrative purposes only and form no part of the claimed design.

1 Claim, 6 Drawing Sheets
